F. W. KREMER,
BEAD FOR OUTER CASINGS FOR PNEUMATIC TIRES.
APPLICATION FILED MAY 22, 1913.

1,202,855.

Patented Oct. 31, 1916.

UNITED STATES PATENT OFFICE.

FRANKLIN WILLIAM KREMER, OF CARLSTADT, NEW JERSEY.

BEAD FOR OUTER CASINGS FOR PNEUMATIC TIRES.

1,202,855.

Specification of Letters Patent. Patented Oct. 31, 1916.

Application filed May 22, 1913. Serial No. 769,281.

To all whom it may concern:

Be it known that I, FRANKLIN W. KREMER, a citizen of the United States, residing at Carlstadt, in the county of Bergen and State of New Jersey, have invented a new and useful Bead for Outer Casings of Pneumatic Tires, of which the following is a specification.

The present invention relates to improvements in beads for outer casings of pneumatic tires, the primary object of the same being the production of a bead in which a plurality of strands of wire are disposed in parallel relation so that the traction strain will be thrown upon all of said strands equally, said strands being preferably composed of a non-stretchable wire, such as piano wire, and being coated or held together by means of a plurality of layers of spirally wound tape, said tape being provided with an adhesive which due to the compression of the tape in winding about the strands is forced into the interstices between the strands so that when the bead is properly vulcanized within the rim engaging portions of the outer casing, a homogeneous vulcanized member will be produced.

A further object of the present invention is the provision of a bead which is either circular or triangular in cross section, according to the use to which it is to be placed.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

In the drawings—Figure 1 is a side elevation illustrating the primary step in forming the coils of the bead. Fig. 2 is a section on line 2—2 of Fig. 1. Fig. 3 is an enlarged detail view of the splice employed for connecting the free terminals of the strands together. Fig. 4 is a longitudinal sectional view through the tape wound bead before the vulcanizing step. Fig. 5 is a cross section thereof. Fig. 6 is an enlarged detail view of a vulcanized circular bead. Fig. 7 is a cross section therethrough. Fig. 8 is an enlarged view of a triangular vulcanized bead. Fig. 9 is a cross section therethrough. Fig. 10 is an enlarged detail sectional view

showing the triangular bead embedded within the rim engaging portion of an outer casing.

Referring to the drawings, and reciting the process from its initial step to the finished article, the piano wire has one terminal bent as at 1 and inserted within the peripheral socket 2 of the reeling wheel 3, said wheel being provided with the strand forming portion so that the strands 4, preferably five in number may be positioned as clearly shown in Figs. 1 and 2, so as to provide the overlapping end 5, which due to the gage notch 6 is extended the desired distance to produce the sufficient splice as at 5—5' Fig. 3.

When the strands are formed as shown in Figs. 1 and 2, the beaded tape (not shown) is wound about the strands at two points beyond the strand 1 and the end of the terminal 5, so that said strands are held in the proper relative position and shape. The terminal constituting the bent portion 1 is straightened and the terminals 1 and 5 are then placed in a winding machine, and twisted as indicated in Fig. 3, after which the adjacent faces of the overlapping ends are soldered together to produce a homogeneous splice. The thus fastened metal bead is then placed in the grooved wheels of the bead forming machine set forth in a co-pending application Serial No. 769,282 filed August 18, 1914, and has first wound thereupon the inner layers 6 of tape, as illustrated in Figs. 4 and 5, said inner layers being spirally wound so as to produce an overlapping effect, the tape being wound as set forth in the above mentioned co-pending application, and the tape being of such a nature as to be saturated with an adhesive substance containing a body of unvulcanized rubber. Sufficient pressure is placed upon the tape during the winding thereof upon the metal strands to force said sticky substance into the interstices between the wires, the purpose of which will presently appear.

After the inner layers of tape, the said inner layers being composed of a single tape wound to overlap, are sufficiently wound upon the full length of the bead, the bead is removed and an outer tape is wound so as to form the two layers 7, the spiral winding of the same being in an opposite direction to the spiral winding of the layers 6, thus producing a means to retain the strands 4 of the metal bead in the proper aligned and

parallel position at all times. The tape wound bead is now placed in a mold, which is provided with cavities, such cavities conforming in cross section to the desired shape 5 of the bead. This mold is preferably constructed with sufficient cavities to take all sizes of a given profile. The mold is then placed in a curing process and semi-cured under pressure, this semi-curing causing the 10 gum to flow and fill the interstices between the strands. The bead is allowed to remain under heat and pressure a sufficient length of time to partially vulcanize the rubber, the partial vulcanizing serving to solidify the 15 bead. This step is an exceedingly important one, as there is insufficient pressure brought to bear upon the bead after it is placed within the rim engaging portion of the outer tire casing, to properly solidify the bead.

20 The thus formed bead, as clearly shown in Figs. 4 and 5, is coated with unvulcanized rubber 8 to form the bead as shown in Figs. 6 and 7, the same being not fully vulcanized so that when inserted within the rim engaging 25 portions 10 of the outer casing, as illustrated in Fig. 10, the same is fully vulcanized with the rubber thereof so as to form in reality an integral mass with the rim engaging portion 10 and with the strands 4 of wire disposed centrally thereof and in the portion thereof 30 which will render the bead more durable and efficient.

The form of bead, as shown in Figs. 8, 9 and 10, is of triangular shape in cross section, the tape portions 6 and 7 being wound 35 upon the strands 4, as illustrated and above described, and embedded in the unvulcanized rubber as at 9 in Figs. 8 and 9 and positioned

within the rim engaging portion of the tire as shown in Fig. 10 to be vulcanized to form 40 a homogeneous mass therein.

It has been found when the tire is provided with a bead of this character, that is where the strands 4 are of the same length and are composed of a substantially non-stretchable 45 metal, as piano wire, that an exceedingly strong bead is provided, and that the maximum torsion thrown upon the tire in rounding curves, will not break the bead, such bead thus increasing the life of the tire, and being 50 more practical and durable than is a twisted or braided wire bead.

What is claimed is:

1. A reinforcing element for a tire bead, comprising a plurality of strand elements 55 bound closely together with a spirally wound, overlapped tape carrying an adhesive which enters between certain of the strand elements, the adhesive being partially vulcanized.

2. A reinforcing element for a tire bead, comprising a plurality of strand elements; a spirally wound, overlapped tape inclosing the strand elements; and a second tape inclosing the first and spirally wound thereon 65 in a reversed direction in overlapped convolutions, both tapes being coated with a vulcanizable adhesive.

In testimony that I claim the foregoing as my own, I have hereto affixed my signature 70 in the presence of two witnesses.

FRANKLIN WILLIAM KREMER.
